UNITED STATES PATENT OFFICE

171,958

COMBINED DIAL AND HANDS FOR A CLOCK OR SIMILAR ARTICLE

Daniel Spooner, Long Beach, N. Y.

Substituted for abandoned application Serial No. 22,091, October 31, 1952. This application May 22, 1953, Serial No. 25,169. Term of patent 14 years

(Cl. D42—1)

To all whom it may concern:

Be it known, that I, Daniel Spooner, a citizen of the United States, residing at Long Beach, New York, in the county of Nassau, State of New York, have invented a new, and ornamental Design for a Combined Dial and Hands for a Clock or Similar Article, of which the following is a specification, reference being had to the accompanying drawing, forming part thereof.

Fig. 1 is a top plan view of a combined dial and hands for a clock or similar article embodying my new design, and

Fig. 2 is a side elevational view thereof.

This application is a substitute for applicant's prior case, Serial No. 22,091, filed October 31, 1952, which is now abandoned, no priority being claimed in view of the lack of continuity between said applications.

I claim:

The ornamental design for a combined dial and hands for a clock or similar article, as shown.
